UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,214,482.

Specification of Letters Patent. Patented Jan. 30, 1917.

Application filed June 30, 1911. Serial No. 636,201.

To all whom it may concern:

Be it known that I, BURNHAM C. STICKNEY, a citizen of the United States, residing in Elizabeth, in the county of Union and State of New Jersey, have invented certain new and useful Improvements in Combined Type-Writing and Computing Machines, of which the following is a specification.

This invention relates to combined type-writing and computing machines of the kind in which a relative step-by-step movement is effected between the master wheel and a system of computing wheels concomitantly with the letter-feeding movements of the carriage of the typewriting machine, and in which a rotation or movement of the master wheel or device is effected as each key is operated. In this class of machines there is liability, especially during rapid operation of the machine, of the master-wheel to be rotating while the typewriter carriage is in motion. In other words, during rapid operation, there may be overlapping of movements of the master-wheel and the carriage. Such overlapping of movements may result in errors in the computation. To attain as a result, increased accuracy in machines having this tendency of the master-wheel and typewriter carriage to move at times simultaneously, it has heretofore been proposed to prevent such simultaneous movement. One of the ways proposed consists in providing a stop which prevents the operation of the master-wheel by or through the keys, unless said master-wheel is in proper relation with one of the computing wheels. While the provision of such means may prevent simultaneous movement of the computing wheels and carriage, it makes it necessary to operate the machine at a lower speed, which is confusing to the operator, and liable to lead to mistakes if the keys fail now and then to yield when pressed upon. Another mode of operation, depending on the same principle as above suggested, has been to prevent the carriage from starting to move until after the rotation of the master-wheel, but this does not permit of as high speed of operation of the typewriting machine as is desirable in some cases. Operating on the same principle, it has also been proposed to let the typewriter carriage control the rotation of the computing mechanism, so that the computing mechanism cannot turn until the carriage has completed its letter-feeding

movement, and thus brought about a proper relation between the master-wheel and a computing wheel. It will be noted that in all of the above modes of operation that have been proposed, the simultaneous operation of the computing wheels and the carriage is prevented.

The main object of the present invention is to secure accuracy in a machine of the general character referred to, and at the same time permit high speed of operation of the typewriting machine. To this end, there is no attempt made to prevent simultaneous movement of the carriage and computing wheels, but, on the other hand, such simultaneous movement is permitted, but at the same time it is assured that the movement of the master-wheel out of engagement with the wheel it has just been turning does not take place until said wheel has completely finished its turning movement, even though during such turning movement of the computing wheel by the master-wheel, the carriage may be in motion. In other words, the master-wheel is maintained in engagement with the live computing wheel, that is the wheel to be turned or the one being turned a length of time sufficient to insure a full turning of said wheel independent of the movement of the carriage. In this way the carriage steps at its normal rate, but the master-wheel may not move necessarily with it, but sticks to the live computing wheel as long as is necessary to fully turn said wheel.

The improvements are illustrated in connection with a master wheel which is connected up to the paper carriage to travel therewith, while the system of computing wheels remain stationary; but it will be understood that the invention is applicable to machines in which the computing wheels travel step-by-step while the master wheel remains stationary; or in which both master wheel and computing wheels travel simultaneously but in opposite directions.

According to this invention, when or immediately before the typewriter carriage comes to rest in its letter-feeding movement, the master wheel jumps to the next computing wheel in the system, that is, the next wheel of lower denomination, instead of remaining in mesh with the computing wheel which it has just rotated. This jumping of the master wheel is effected automatically,

and anticipatively or in advance of the next letter-feeding movement of the carriage.

In machines in which the computing wheels are rotated by source of power, as for instance the Underwood combined typewriting and computing machine, to which one form of the present invention is shown as applied, it is usual for the figure type key to set a computation pin and also to cause the typewriter carriage to feed. At the conclusion of the carriage-feeding movement, the computing mechanism revolves, and the master wheel thereof remains uselessly in engagement with the same computing wheel which it has just turned, and which is therefore "dead," until the next key is operated.

In the form of the present invention illustrated in the drawings, there is a relative positioning of the master-wheel and computing wheels independently of the carriage. Preferably the master wheel jumps to the "live" computing wheel, or the computing wheel of next lower denomination, independently of the carriage, and this movement preferably takes place just as the carriage comes to rest upon completing its letter-feeding movement.

The master-wheel and parts traveling therewith are very light, and move quickly, so that they can jump the short distance required, by the time the paper carriage comes to rest, even if said parts are released for such jumping movement during the last part of the letter-feeding movement of said carriage. The master wheel therefore remains in engagement with said live wheel, *i. e.* the computing wheel of next lower denomination to that which has just been rotated, from the time the paper carriage comes to rest, almost until the time when it comes to rest again, thus greatly prolonging the interval during which the master wheel is in engagement with the live wheel. The master wheel does not linger, as heretofore in this machine, in engagement with the computing wheel which it has turned, and which is therefore dead, but jumps to the computing wheel which it is to rotate next, that is, the live wheel, and remains in engagement with the live wheel from the time the carriage comes to rest, after one figure is printed, practically the entire time until said paper carriage comes to rest after the next figure is printed. In other words, there is practically no interval of time in which the master wheel is in engagement with a dead computing wheel. This saving of time is a vital one in machines which are operated at such high speed as typewriting machines. This feature, consisting of effecting a relative traveling or positioning movement between the master wheel and the system of computing wheels in advance of or out of time with the corresponding movement of the carriage, may be employed in many

ways, and in different kinds of machines, and is not limited to machines of the class illustrated, in which the computing wheels are power-driven, and in which the independent positioning or shifting movement between the master wheel and the computing wheel occurs just as the typewriter carriage is coming to rest, or even during the movement of the carriage, since such shifting movement may occur regardless of the carriage, as soon as any computing wheel is rotated and hence becomes dead.

The scope of the invention includes any means whereby a simultaneous drive of the computing wheels and stepping movement of the carriage is permitted in a machine of this character.

The scope of the invention also includes any means whereby any relative shifting movement is effected between the master wheel and the computing wheels in advance of the corresponding carriage-feeding movement, or independently of such carriage-feeding movement, to lengthen the time during which the master wheel remains in engagement with the live computing wheel.

In the present form of the invention, after the relative independent jumping or shifting movement has been effected between the master wheel and the system of computing wheels, so that the master wheel effects the advance connection with the live computing wheel, provision is made for maintaining this connection during the ensuing letter-feeding movement of the carriage, that is, the master wheel remains in connection with said live computing wheel until the ensuing letter-feeding movement of the carriage is almost completed, and then jumps again to the wheel of next lower denomination.

It should be explained that in machines in which the computing wheels are rotated by power applied by means of finger keys, and in which the wheels are rotated during the down strokes of the finger keys, and hence in which the rotation is completed by or before the time that said down stroke of the key is finished, the relative jumping or shifting movement of the master wheel and computing wheels may begin at about the beginning of the ensuing letter-feeding movement of the carriage, so that the master-wheel will be in connection with the computing wheel of next lower denomination, during the early part of the letter-feeding movement of the carriage, whereby in case the next key is depressed by the time the carriage has made only a short portion of its movement, the appropriate computing wheel will be turned by the master wheel. The type may perhaps strike the paper the instant the carriage stops, or possibly a little before; but the computing wheel is rotated properly, so that no liability of error can arise.

The principle of operation just set forth

is substantially that embodied and disclosed in my co-pending application Serial No. 654,535, filed October 13, 1911.

It is the usual practice in said Underwood machine, to set the computing pin during the down stroke of the type key, and to cause the computing mechanism to rotate upon the upstroke of the type key, thus losing time, the loss arising partly from the pause of the finger on the key at the bottom of the stroke; and another object of the present invention is to reduce or avoid the loss of time between the setting of the computing pin and the rotation of the computing wheel. To this end I contrive to cause a single down stroke of the key to effect both the setting of the computing pin and the rotation of the computing mechanism. I provide means whereby the computing mechanism is released from the key upon the computing pin being set. This is done at or during the down stroke of the key, so that certain members of the computing mechanism can return to normal positions in advance of the return of the key to normal position, and preferably in advance of the completion of the down stroke of the key. During the return of said certain computing devices to normal positions, the rotation of the computing wheel occurs; and it will frequently happen that the rotation of said wheel will be completed before the operator fully releases the key, or even before the key starts on its return movement upon such stroke, and hence before the carriage of the typewriter starts to feed; although if the machine is operated rapidly, it may happen that the rotation of the live computing wheel will not be completed until after the typewriter carriage has started to feed. From the foregoing explanation, it will be understood that such movement of the paper carriage during the turning of the live computing wheel is provided for; the master wheel and the live computing wheel remaining in mesh not only while the carriage is stationary, but also during the principal portion of the feeding movement of the carriage. Upon the return of the key to normal position, it reconnects automatically with said certain members of the computing mechanism, for effecting subsequent operation of the latter. It will be understood, however, that the automatic releasing mechanism between the keys and the computing devices may be employed where the computing wheels are driven by finger-power applied to the keys, instead of by a separate source of power, and will result in increase of speed and accuracy of operation, as compared with prior key-driven computing machines.

Other objects and advantages will hereinafter appear.

In the accompanying drawings, Figure 1

is a sectional side elevation of an Underwood combined typewriting and computing machine, showing the present improvements applied thereto. Fig. 1^a is a sectional elevation of letter-feeding mechanism. Fig. 2 is a diagram to illustrate the connection of the pin-carrying escapement wheel of the computing mechanism, with the master wheel thereof. Fig. 3 is a part sectional rear elevation, showing in normal positions, the devices for effecting the anticipative advance movements of the master wheel. Fig. 4 is a fragmentary sectional rear elevation of means associated with the tabulating mechanism for automatically disconnecting the master wheel from the paper carriage of the typewriter. Fig. 5 is a detail of a spring device for lifting a hook which intermittently connects the master wheel to the typewriter carriage. Fig. 6 is a part-sectional plan view of the connections of the typewriter carriage to the computing wheels. Fig. 7 is a perspective view of the hook mechanism which intermittently connects the master wheel to the typewriter carriage. Fig. 8 shows a form of column stop to operate with said hook. Fig. 8^a shows an ordinary column stop. Fig. 9 is an elevation of a set of interfering blades which prevent two or more figure keys from being depressed simultaneously. Fig. 10 is a sectional detail of the connection of the master wheel to its driving gears. Fig. 11 is a perspective view, showing the automatically releasing connections between the numeral type keys and the computing mechanism. Fig. 12 is a rear elevation of the automatic trip connecting the keys to the computing devices. Fig. 13 shows a position of the trip when the key is fully depressed. Fig. 14 illustrates the operation of the interfering blades seen at Fig. 9.

Numerical type keys 1 and alphabet keys 2 are mounted upon the forward ends of levers 3, which operate bell cranks 4 to swing type bars 5 upwardly and rearwardly against the front side of a platen 6, which is mounted on a carriage 7, the latter driven by a spring 8 and strap 9, Fig. 3, and having a rack 10 meshing with a pinion 11 connected to an escapement wheel 12. This wheel is controlled by dogs 13, 14, the latter driven by a frame 15 pivotally supported upon idle arms 16, and carrying at its front end a segmental universal bar 17, which is driven by heels 18 on the type bars, as usual in the Underwood typewriting machine.

Each numerical key lever has a finger 19 to catch upon a pendent hook-shaped pawl or trip 20, which is pivoted at its upper end at 20^a to an arm 21 of a bell crank. The other arm 22 of said bell crank is connected by a link 23 to a lever 24, which carries at its free end a cam 25, which at the swinging of said lever by means of said key, en-

gages one of a circular set of escapement or index pins 26, to project it from the opposite side of a wheel 27, upon which said pins are mounted. This escapement-pin 5 wheel or index wheel and the parts driven thereby, as well as the means for driving said wheel, are set forth in pending applications No. 556,378 filed April 19, 1910, and No. 574,813, filed August 1, 1910, the escapement pin wheel 27, in said applications, being driven by a motor 28, which has a frictional connection with a train of gearing 29, the latter including a bevel gear 30 on the same shaft as a gear 30^a which meshes 10 with a pinion 31 on the shaft of said escapement pin wheel 27. Hence there exists a 15 constant tendency to rotate said wheel.

A four-toothed pinion 32 is engaged and rotated by the pins 26 in the order of their 20 projection; the rotation of said pinion 32 being controlled by a secondary escapement wheel 33, which normally is arrested by a feeding dog 34 operated by the keys 1. The movement of the dog is effected through 25 any lever 24. Said levers bear upon a universal plate or member 35, mounted upon a sliding rod 36, and having a returning spring 37; said plate connected by a head 38 to a lever 39, which thrusts a link 40 to rock an arm 41 upon a rock-shaft 42 which carries said dog 34. This movement of the 30 rock shaft to the position seen at Fig. 11, permits the tooth of the secondary escapement wheel 33 to escape from the dog 34, and to be temporarily detained (Fig. 11) by 35 a dog 43 also fixed on the rock shaft 42 in front of the dog 34.

Upon the return movement of the rock shaft 42 (effected by the spring 37) the escapement wheel 33 slips off from the dog 43, and the pin 26 shown in engagement 40 with pinion 32, turns the latter and escapes therefrom, while such pin 26 as has just been projected is carried by said wheel 27 into engagement with the pinion 32, thereby bringing the next tooth of escapement wheel 33 into engagement with the dog 34. A fixed cam 43^a, Fig. 11, returns the set pins to normal positions.

50 During the descent of the key and trip 20, and preferably about half-way of the stroke of the key, an arm 44 provided on the trip 20 above the pivot 20^a, engages a stop or tripper 45, which may be in the form 55 of a pin projecting from a plate 46, which carries the bell crank 21, 22; and the trip is swung on its pivot 20^a to disengage it from the finger 19 on the key lever, as seen at the right-hand portion of Fig. 12. This 60 permits the spring 37 to return the universal plate or member 35 to normal position, together with the parts 39, 40, 41, 42, 34 and 43, thus permitting the main computation wheel 27 to be rotated, together with one of 65 the digital computing wheels (presently to

be described) in advance of the return of the key 1 to normal position, and this return of the above mentioned parts may occur during the final portion of the down stroke of said key, since these parts may be 70 very light and of quick action.

The lever 24, pin 23, and bell crank 21, 22 are returned to normal positions by a spring 47 (Fig. 14) while the key lever 3 is descending to the bottom of the stroke, 75 as seen at Fig. 13, or while it is momentarily held in such position by the operator's finger. The operator cannot prevent the instant return of the disconnected computing parts to normal positions, and the instant rotation of the computing wheels. Upon relief of the key from pressure, it is returned by the usual spring 48, Fig. 1, and the trip 20 is snapped under the finger 19 by means of a spring 49, with which each 80 trip is provided.

The trips preferably pass through perforations 50 in a rod 51, having means, such as 52, whereby it may be shifted endwise or to the left at Fig. 11, to withdraw all of 90 the trips, for silencing the computing mechanism.

The connection between the pin-carrying escapement wheel 27 and the dial wheels comprises a pinion 53 in mesh with said 95 bevel gear 30, and fixed upon a shaft 54 which carries at its other end a pinion 55 to mesh with a pinion 56 on a vertical shaft 57, upon which is provided a bevel pinion 58 meshing with a pinion 59 upon a shaft 100 60, upon which slides a master wheel 61, Fig. 6, the latter being splined upon the shaft, which for this purpose is made square in cross-section. The master wheel has opposite teeth 62, which work in notches 63 in 105 computing wheels 64, which are geared to mesh with gears 65, consisting of dial wheels 66. The tens-carrying mechanism is of the usual construction, and is not shown. These computing and dial wheels are mounted in 110 a casing 67, which is secured upon a bracket 68, the latter secured to the framework of the machine. The master wheel 61 is swiveled to the end of a hollow arbor 69 which does not rotate, but is arranged to slide with 115 the master wheel to and fro upon shaft 60. This arbor 69 projects from one end of a slide or carriage 70 which also comprises a tubular member 71 sliding upon a fixed rod 72. This master wheel carriage 70 is connected by a pin 73 to a slot 73^a in a lever 74 fulcrumed at 75, and at its rear end connected by pin 76 and slot 76^a to a block 77 sliding in a tubular guide 78, and carrying one end of a flexible stem 79, a hook 80 upon 120 the other end of which is engageable with one or more of a series of lugs 81 adjustable along a rack 82 fixed upon the typewriter carriage 7; the teeth in said rack being 125 formed at letter-spacing intervals, as usual. 128

These lugs 81 at Fig. 8 have extensions 81^a to engage the hook 80. Upon the same rack may be carried ordinary column stops 83, to engage denomination stops 84 carried upon 5 levers 85 bearing keys 86; said stops 84 being constructed to coöperate with either 81 or 83 to arrest the carriage. It will be seen that any lug 81, by means of said hook, is enabled to swing the lever 74, and drive 10 the master-wheel carriage 70 in a direction opposite from that taken by the paper-carriage 7 of the typewriter; the master wheel communicating with the wheel of highest denomination and proceeding to that of 15 lowest denomination.

The hook is released from the extensions 81^a, (against tension of spring 86^a) by means of a trip stud 87, fixed upon a bracket 88, and, when so tripped, a spring 89, connected 20 to the lever 74, returns the latter to normal position (see dotted lines, Fig. 6) with the master wheel just beyond the system of computing wheels seen at Fig. 6. The hook will be carried back by spring 89 and engage 25 the next lug 81, and again be carried along step-by-step with the carriage 7 to perform cross-adding, as set forth in said application No. 574,813; that is, numbers may be written in various columns upon the work 30 sheet, and as the several numbers are written along one line of writing, they are accumulated upon the computing wheels; the master wheel carriage 70 moving step-by-step with the paper carriage 7 until one 35 number is written, and then jumping back to be reconnected by the hook 80 to the paper carriage, so that the latter may continue its run while another number is being written upon the same line and accumulated 40 upon the computing wheels, and so on.

The means above described for disengaging the hook 80 from any one of the lugs 81 operates during the movement of the carriage in letter-feeding direction. When, 45 however, the carriage is returned to normal position, it is necessary to cam the hook out of engagement with any lug 81, with which it may be engaged, and for this purpose, there is provided an interceptor stud 90 50 (Fig. 4) upon the framework, which engages a cam 91 on the hook 80 to depress the same during such return movement of the carriage, so as to clear shoulder 92 on the hook.

55 While the present improvements are shown in connection with a jumping master wheel, it will be understood that they are also applicable to a machine in which the master wheel remains stationary while the system of computing wheels jumps; it will be further understood that the improvements are also applicable to machines in which there is no such relative jumping movement between the typewriter carriage and any part 60 of the computing mechanism; and also to

still other kinds of combined typewriting and computing machines. In the present instance, the lever 74 which connects the hook 80 to the computing wheel carriage 70, is arranged to have an anticipative shifting 70 movement independent of said hook 80, or of the paper carriage 7. This movement may be effected in one direction by a spring 95, Fig. 3, and in the other direction by any tooth of the carriage escapement wheel 12. 75 The latter acts upon a pallet 96 which is pivoted at 97 to enter between the teeth of said escapement wheel. The pallet 96 has a cam edge 98 to be engaged successively by the teeth of the escapement wheel, to force 80 the same outwardly or to the left at Fig. 3. This pallet 96, to which said spring 95 is connected, is also connected by a link 99, rocker 99^a and link 99^b to an arm 100 of a shiftable support for the lever 74; another 85 short arm 101 of said support carrying the pivot or fulcrum 75 of said connecting lever. The pivot 101^a of said support is close to the pivot 75 of said lever 74, forming a sort of eccentric fulcrum for the lever 74; and these 90 pivots may normally occupy a dead-center relation, as at Fig. 6, to avoid the liability of accidental movements of lever 74. The pivots 101^a and 75 may be so close together as to give the spring 95 sufficient purchase to 95 control the position of the support 101, to prevent accidental movement thereof. Stops 101^b and 101^c limit the stroke of the shiftable support 101. In this form of the invention, 100 the parts are preferably so arranged that just before the completion of the letter-feeding movement of the carriage, the pallet 96 escapes from a tooth 102 of the escapement wheel or rack 12, and the spring 95 pulls said pallet to the Fig. 3 position. This 105 movement of the pallet acts through the link 99, rocker 99^a, link 99^b and shifting support or bell-crank 100, to swing the pivot 75 to the left from the dotted-line to the full-line position at Fig. 6, a distance equal to about 110 one-half of a letter-space movement of the carriage, (or one-half of the pitch of the teeth on the rack 82). This fulcrum 75 is half-way between the pin 76 and the ends of 115 said lever 74, so that this movement of one-half a letter-space of said fulcrum 75 is doubled at the front end of lever 74, so that said master-wheel carriage 70 moves to the left substantially a full letter-space from its 120 extreme right-hand position to the position seen at Fig. 6. This movement of lever 74 is from the dotted-line to the full-line position at Fig. 6; the rear end of the lever remaining 125 stationary, and spring 89, connected to said rear end, offering little or no opposition to such movement. In consequence of this movement of the lever 74, the master wheel 61 is advanced anticipatively into engagement with that computing wheel 64 which is 130 next to operate, so that at the moment of 135

completion of the letter-feeding movement of the typewriter carriage, the master wheel is in position to operate the live computing wheel. At Fig. 6, the master wheel is in mesh with the computing wheel 64 of highest denomination, which is seen at the right-hand end of the set of computing wheels. It will be understood that when the master wheel carriage is slid to the extreme right at Fig. 6 by spring 89, said carriage may be shifted to the left by spring 95 without bringing master wheel 61 into engagement with any computing wheel; such engagement with the first computing wheel being effected by hook 80 at the first letter feeding movement of the carriage 7 which occurs after the engagement of the hook with a lug 81.

Under the depression of a figure key, and printing of a type, the universal bar 17 is operated, and the usual carriage feeding dogs 13, 14 are actuated in one direction; the carriage 7 remaining stationary; but at the release of said key from pressure, the dogs 13, 14 permit the rotation of the escapement wheel 12, and a movement of the carriage under the tension of spring 8; and the succeeding tooth 103 of the escapement wheel engages the pallet 98, and cams the same outwardly or to the left at Fig. 3 against the tension of spring 95, the movement of 98 being most rapid at the beginning of the stroke, to compensate for the relatively slow movement of the fulcrum 75 toward the right at Fig. 6. This movement is communicated through the link 99, rocker 99^a and link 99^b to the shifting lever 101, and the fulcrum 75 upon said shifting lever is returned to the right at Fig. 6 a distance (usually one-twentieth of an inch) equal to half of a letter-space movement of the carriage 7. At the same time that said lever 101 is returning, the rear end of the lever 74 is moved to the right a full letter-space distance, or twice as far to the right as the fulcrum 75 moves. In consequence, the forward end of the lever remains stationary or approximately so, and hence the master wheel 61 remains in engagement with the live computing wheel during a substantial portion of the travel of the carriage 7. Thus, the time during which the master wheel is in engagement with the computing wheel of the next lower denomination to that upon which it has last acted, is greatly extended with the effect of permitting a higher speed of manipulation of the machine, and rendering the operator less dependent upon or wholly independent of locking devices, which have been placed in machines, for the purpose of preventing the computing mechanism from operating before the paper carriage travels, and for other purposes. Thus it will be seen that upon a depression of a key 1, not only is the

lever 3 depressed to throw the numeral type to the platen, but a corresponding pin 26 is also set upon the pin-carrying escapement wheel 27, and the pin-setting devices return to normal positions, together with the devices which control the escapement wheel 33, in advance of the return to normal position of the depressed key 1, and usually before the completion of the descent of said key, or at least before it begins to return, so that the escapement-pin wheel 27 may begin at once to revolve under the influence of the motor 28.

It will be seen that the carriage 7 cannot start to move in advance of the rotation of the escapement-pin wheel 27, because the carriage 7 is not released until the key 1 begins its upward or return movement, at which time, the escapement pin wheel 27 is rotating, or has completed its rotation, together with the master wheel and the associated computing wheel. Preferably the universal bar 17 is not moved by the type bar 5 until the trip 20 has released the computing devices from the type-bar operating key, so that even a slight movement of carriage 7 cannot occur prior to the release of trip 20. It will also be seen at Fig. 10 that the teeth 62 of the master wheel 61 are thinner than those of the computing wheel, so as to allow some play of the master wheel in axial direction without getting out of mesh with one computation wheel and into mesh with another. At the first part of said return movement of the key 1, the carriage 7 is released for advance movement, and by means of pallet 96, the master wheel carriage 70 is held stationary, so that ample time is given in which to effect the rotation of said master wheel before the latter is carried by spring 95 out of engagement with the live computing wheel.

Heretofore in power-driven computing machines of this class, the movement of the master wheel in axial direction has been simultaneous with the movement of the paper carriage 7; but according to the present invention, it may be delayed until the movement of the paper carriage is nearly completed, which gives the master wheel a much longer time to dwell in mesh with the computing wheel upon which it is acting.

As already explained, at the final part of the letter-feeding movement of the paper carriage 7, the pawl 96 escapes from the tooth 103 of the escapement wheel 12, and acts through link 99 and shifting lever 101 to shift the forward end of lever 74 to the left about a full letter-space, together with the carriage 70 and the master wheel 61, so that the latter is brought into engagement with the computing wheel of next lower denomination. Thus the interval of time during which said computing wheel is out of engagement with the live computing

wheel is reduced to a minimum, and there is a corresponding increase in accuracy and speed of operation of the machine.

It will be understood that in said Underwood machine, the typewriter carriage escapement wheel 12 does not rotate backwardly at any time, so that there can be no false movement of the pallet 96 and its connections from this source; a pawl-and-ratchet mechanism being usually provided between the pinion 11 and said escapement wheel 12, to permit the carriage to run back without turning said escapement wheel.

Preferably means are provided for silencing the pallet 96 when the carriage 7 is out of the computing field. To this end, a pin 104 is provided upon the hook 80, to strike an arm 105 and turn the same, whenever said hook is released from the lug 81 and returned by the spring 89; the contact between said pin 104 and said arm 105 occurring just before the end of the hook stem 79 strikes an adjustable screw stop 106 in the housing 78. The arm 105 is therefore given a slight vibration to the left at Fig. 3, and rocks its shaft 107 and swings downwardly an arm 108, thrusting down a link 109, which, at its lower end, is pivoted to an arm 110, Fig. 1, on a swivel or rocker 111, Fig. 3, upon which said pallet 96 is pivoted at 97. This swings the pallet to the right at Fig. 1, out of the path of the teeth of the escapement wheel 12, so that no movement of the pallet occurs when the carriage 7 is out of the computing field. The spring 95 is set diagonally, as seen at Fig. 6, so as to return the parts 96, 111, 110, 108, 105, to normal positions (with lug 112^a on arm 105 resting against stop 112^b) whenever the hook 80 is caught by the lug 81 and carried a step to the right, as seen at Figs. 3 and 6, the master wheel 61 being now brought into position for use, as above explained; said master wheel occupying a position clear of the computing wheels and to the right of its position in Fig. 6, whenever the stem 79 engages the screw-stop 106. The devices 105, 108, 110 and 111, may however be omitted in some cases, and the silencing of the pallet 96 dispensed with. When the carriage 7 is positioned by means of a key 86, the master wheel will be found in mesh with a computing wheel of the same denomination as the operated key 86.

It will be understood that in some machines the devices for automatically re-positioning the master wheel in anticipation of the next movement of the typewriter carriage may be employed without the devices which automatically release the computing members from the keys, and vice versa. Still other portions of the invention may be used separately; and wide variations may be resorted to within the scope of the several features of the invention.

Where in the claims I use the terms "mas-

ter wheel" or "computing wheel", it will be understood that I mean to include all equivalent devices; such for instance as bars or racks provided with or connected to suitable dials or indexes.

Having thus described my invention, I claim:

1. The combination with a letter-feeding carriage, and two primary elements having relative step-by-step movements concomitantly with the movements of said carriage, one of said primary elements being a master wheel or member, and the other of said primary elements comprising a set of computing wheels or members individually actuatable by said master wheel, of means for automatically effecting relative positioning or shifting of said primary elements to engage the master wheel with the live computing wheel in advance of the corresponding feed movements of said carriage; to prolong the interval during which the master-wheel is engaged to the live computing wheel.

2. The combination of a carriage and escapement mechanism therefor, two primary elements having relative step-by-step movements concomitantly with the movements of said carriage, one of said primary elements being a master wheel, and the other of said primary elements comprising a set of computing wheels individually actuatable by said master wheel, and means controlled by said escapement mechanism for effecting relative positioning of said primary elements to prolong the interval during which the master wheel is engaged to the live computing wheel.

3. The combination with a letter-feeding carriage, and two primary elements having relative step-by-step movements concomitantly with the movements of said carriage, one of said primary elements being a master-wheel, and the other of said primary elements comprising a set of computing wheels or members individually actuatable by said master wheel, of means for automatically effecting a relative shift or positioning of said primary elements to engage the master wheel with the live computing wheel during the feeding movement of the typewriter carriage.

4. The combination of a carriage, an escapement or feeding mechanism therefor, including an escapement wheel or rack, two primary elements having relative step-by-step movements concomitantly with the movements of said carriage, one of said primary elements being a master wheel, and the other of said primary elements comprising a set of computing wheels individually rotatable by said master wheel, a pallet engaging said escapement wheel, a connection from said pallet to one of said primary elements, and a spring to effect a limited shift or positioning of the same with relation to

the other of said primary elements when said pallet escapes from a tooth of said escapement wheel.

5. The combination of a carriage, an escapement or feeding mechanism therefor, including an escapement wheel, two primary elements having relative step-by-step movements concomitantly with the movements of said carriage, one of said primary elements 10 being a master wheel, and the other of said primary elements comprising a set of computing wheels individually rotatable by said master wheel, a pallet engaging said escapement wheel, a connection from said pallet 15 to one of said primary elements, and a spring to effect a limited shift or positioning of the same with relation to the other of said primary elements when said pallet escapes from a tooth of said escapement 20 wheel; means provided for automatically silencing the pallet when the machine is not computing.

6. The combination of a letter-feeding carriage, two primary elements, one being a 25 master wheel and the other comprising a set of computing wheels individually rotatable by said master wheel, one of said elements mounted to travel, means to connect said traveling element to said carriage, means to 30 disconnect said traveling element from the carriage and reconnect it thereto at a different point, and means for affecting the connection between said carriage and said traveling element in a manner to cause said 35 traveling element to shift to the extent of not more than a letter-space independently of the carriage, to prolong the interval during which the master wheel is engaged to the live computing wheel.

40 7. The combination with a set of numeral keys, of a set of computing members, a master member, means brought into action under control of said keys, for both causing the rotation of the master member and determining the extent of its rotation, and means under control of said keys for releasing said key controlled means from the keys to enable said means to act independently of the return of the keys to normal positions.

45 8. In a computing machine, the combination with computing mechanism including denominational members, a master member and a step by step feeding carriage, of means controlled by said carriage for producing 50 relative movement between the denominational members of the computing mechanism and master member, said means including devices operating to maintain any denominational member of the computing mechanism 55 and master member in driving relation during a substantial part of each step of the carriage movement.

60 9. In a combined typewriting and com-

puting machine, the combination with computing mechanism including denominational 65 members, a master member and a step by step feeding carriage, of means controlled by said carriage for producing a relative movement between the denominational members of said computing mechanism and said master member to enable a *seriatim* drive of the former by the latter, said means including a spring for moving said master member, said spring being put under tension during letter feeding movement of said carriage and means 70 for releasing said spring from tension at substantially the conclusion of the feeding movement of said carriage whereby the master member and any denominational member of the computing mechanism are 75 maintained in driving relation during a substantial part of each step of the carriage movement.

10. The combination with a set of numeral keys, of a computing mechanism, including a set of computing members, a power-driven master member, means normally restraining said master-member, means brought into action under control of said keys, for both causing the rotation of 85 the master-member and determining the extent of its rotation, and means dependent upon the operation of any key for releasing said key-controlled means from the operated key to enable said master member to 90 perform its function independently of the return of the operated key to normal position.

11. The combination with a set of numeral keys, of a computing mechanism including a set of computing members, a power-driven master wheel, means normally restraining said master wheel, a universal disk or member operable by said keys, means controlled by said universal member for feeding the master wheel, means controlled 100 individually by the keys for determining the extent of feed or rotation of the master wheel, and means dependent upon the operation of any key, for releasing both said universal member and said key-controlled 105 means from the operated key, to enable said master wheel to perform its function independently or in advance of the return of the operated key to normal position.

12. The combination with a set of numeral keys, of a power-driven computation wheel having escapement pins, individual means to enable said keys to set said escapement pins, means normally restraining said wheel from rotation, a universal member operable by any key and controlling the escapement or feeding movements of said wheel, means dependent upon the operation of any key for disconnecting it from both its pin-setting member and said universal 115 member, and means to return said pin-set- 120

125

ting member and universal member to normal positions in advance of the operated key.

13. The combination with computing mechanism of numeral keys, and connections for controlling the action of said computing mechanism, locking means in said connections for preventing computation with another key until a computing action started by one key has been completed, means independent of the return of the key for returning said locking means, and means to enable said connections to be controlled by said keys to permit said keys to start a computing action on their down strokes and to return after having been depressed to start such computing action at any time before or after the computing action has been completed.

14. The combination of keys, spring-returned individual interfering blades connected thereto to prevent the simultaneous operation of two keys, and means between the keys and the blades and dependent upon the operation of the keys for automatically disconnecting any key from its blade, to permit said blade to return in advance of the key, so that another key may be started during the final portion of the return of the first key to normal position, thereby permitting rapid operation of the keys.

15. The combination of numeral keys, computing mechanism controlled thereby and including computing wheels and also including a spring-returned member universal to said keys and forming part of a feeding or rotating mechanism for the computing wheels, and means dependent upon the operation of any key for disconnecting it from said universal member to enable the latter to return to normal position independently of the depressed key.

16. The combination with typewriting mechanism including a carriage, type-operating numeral keys, means controlled by said keys for feeding the carriage, and a computing mechanism including as primary elements a power-driven master wheel and a set of computing wheels, of means normally restraining said master wheel, means controlled by said keys for releasing the master wheel and determining the extent of its rotation, means dependent upon the operation of any key for releasing said key-controlled means therefrom, to permit said key-controlled means to complete its operation in advance of the return of the key, means connecting one of said primary elements to said typewriter carriage, and means for automatically effecting relative re-positioning of said primary elements during the feeding movement of said typewriter carriage.

17. The combination with typewriting mechanism including a carriage, type-oper-

ating numeral keys, means controlled by 65 said keys for feeding the carriage, and a computing mechanism including as primary elements a power-driven master wheel and a set of computing wheels, of means normally restraining said master wheel, means controlled by said keys for releasing the master wheel and determining the extent of its rotation, means dependent upon the operation of any key for releasing said key-controlled means therefrom, to permit said key-controlled means to complete its operation in 70 advance of the return of the key, means connecting one of said primary elements to said typewriter carriage, means for automatically effecting relative re-positioning of said primary elements during the feeding movement 75 of said typewriter carriage, and means for automatically silencing the re-positioning means when the typewriter carriage is out of the computing field.

18. The combination with two primary elements, one consisting of a master-member and the other consisting of a set of computing members, of means for effecting relative lateral step-by-step movement between said 90 primary elements, and means for automatically effecting lateral displacement of one of said elements relatively to the step-by-step moving means, at each step-by-step movement

95
19. The combination with two primary elements, one consisting of a master member and the other consisting of a set of computing members, of mechanism for effecting relative step-by-step movement between said 100 primary elements, and means for effecting automatically an anticipative relative movement between said primary elements whereby engagement is effected between said master member and the live computing 105 member, and for maintaining such engagement during the ensuing movement of the step-by-step mechanism.

20. The combination with a carriage and escapement or feeding devices therefor, of 110 two primary elements, one comprising a master-member and the other comprising a set of computing members, one of said primary elements connected to said carriage, whereby relative step-by-step movement may 115 be effected between said primary elements, and means connected to said escapement devices for effecting a reciprocation of one of said primary elements in a manner to effect engagement between the master-member and 120 the live computing member anticipatively of the feeding movement of said carriage, and to maintain such engagement during such feeding movement of said carriage.

21. The combination with a step-by-step 125 feeding carriage, of two primary elements, one comprising a master-member and the other comprising a set of computing mem-

bers, one of said primary elements connected to said carriage, whereby relative step-by-step movement may be effected between said primary elements, and means for effecting 5 automatically and in advance of the feeding movement of said carriage, an anticipative relative movement between said primary elements, whereby engagement is effected between said master-member and the live computing member, and for maintaining such engagement during the ensuing feeding movement of said carriage.

22. The combination with a step-by-step feeding carriage, of two primary elements, 15 one comprising a master-member and the other comprising a set of computing members, one of said primary elements connected to said carriage, whereby relative step-by-step movement may be effected between said primary elements, a set of numeral keys, a set of trips or releasing devices connected to said keys, step-by-step carriage-feeding mechanism connected to said keys, means connected through said 25 trips to said keys for variably controlling the rotation or driving of said master-member, and means for effecting automatically and in advance of the feeding movement of said carriage, an anticipative relative movement between said primary elements, whereby engagement is effected between said master-member and the live computing member, and for maintaining such engagement during the ensuing feeding movement of said 35 carriage.

23. The combination with a carriage and escapement or feeding devices therefor, of two primary elements, one comprising a master-member and the other comprising a 40 set of computing members, one of said primary elements connected to said carriage, whereby relative step-by-step movement may be effected between said primary elements, a set of numeral keys, a set of trips or releasing 45 devices connected to said keys, means connected through said trips to said keys for variably controlling the rotation or driving of said master-member, and means connected to said escapement devices for effecting 50 a reciprocation of one of said primary elements in a manner to effect engagement between the master-member and the live computing member, anticipatively of the feeding movement of said carriage, and to maintain such engagement during such feeding 55 movement of said carriage.

24. The combination with a carriage and escapement or feeding devices therefor, of two primary elements, one comprising a 60 master-member and the other comprising a set of computing members, one of said primary elements connected to said carriage, whereby relative step-by-step movement may be effected between said primary ele-

ments, a spring for effecting a lateral movement of one of said primary elements in a manner to effect engagement between the master-member and the live computing member, anticipatively of the feeding movement of said carriage, and means connected 65 to said escapement devices for maintaining such engagement during such feeding movement of said carriage.

25. The combination of a letter-feeding carriage having a toothed wheel, two primary elements comprising a master wheel and a set of computing wheels, one of said primary elements connected to said carriage, a spring to effect relative shifting of said primary element to bring the master wheel 75 into engagement with the live computing wheel anticipatively of the feeding movement of said carriage, and a pallet moved by said spring into the path of a tooth of said toothed wheel, to be driven by said tooth during the ensuing feeding motion of 80 the carriage, and caused thereby to maintain the engagement of said master wheel with said live computing wheel during said carriage-feeding movement.

26. The combination of a step-by-step feeding carriage, a master member connected thereto, a set of computing members, and means for automatically jumping said master-member into engagement with the live 95 computing-member in advance of the feeding movement of said carriage and holding said master-member in engagement with said live computing-member during the ensuing feeding movement of said carriage.

27. The combination with a carriage having an escapement wheel, of a master-member connected to said carriage, a set of computing-members, and means to coöperate with said escapement wheel to cause said 105 master-member to jump into engagement with the live computing member anticipatively of the feeding movement of said carriage and maintain such engagement during such feeding movement of said carriage.

28. A combined typewriting and computing machine having computing mechanism, a master member therefor, a step-by-step feeding carriage controlling said master member, and numeral keys controlling said 115 carriage and master member; and comprising, in combination, means for increasing the speed and accuracy of control of said computing mechanism by said keys, including a set of releasing devices connected to 120 said keys, said devices being connected for controlling said master member for variable rotation and said first mentioned means also including means for effecting automatically, anticipatively of the feeding movement of 125 said carriage the jumping of said master member into engagement with the live computing wheel and maintaining such engage-

ment during the ensuing movement of said carriage.

29. The combination of a step-by-step feeding carriage having a toothed wheel, 5 a master wheel connected to said carriage, a set of computing wheels, a spring to effect shifting or jumping movement of said master-wheel to bring it into engagement with the live computing wheel anticipatively of 10 the feeding movement of said carriage, and a pallet moved by said spring into the path of a tooth of said toothed wheel, to be driven by said tooth during the ensuing feeding motion of the carriage, and caused thereby 15 to maintain the engagement of said master-wheel with said live computing wheel during said carriage-feeding movement.

30. The combination with a letter-feeding 20 carriage, of two primary elements having relative step-by-step movements concomitantly with the movements of said carriage, one of said primary elements being a master member and the other of said primary 25 elements comprising a set of computing members individually actuatable by said master member, and means for automatically effecting relative positioning and shifting of said primary elements to prolong the 30 interval during which the master member is engaged with the live computing member.

31. The combination with a step-by-step feeding carriage, of a set of numeral keys controlling said carriage, two primary elements, one comprising a master-wheel and the other comprising a set of computing wheels, one of said primary elements connected to said carriage, a set of trips, devices controlled by said keys through said 40 trips for both causing the rotation of the master-wheel and determining the extent of its rotation; said trips operating automatically to disconnect said key-controlled devices from said keys; and means for returning 45 said key-controlled devices to normal positions independently of said keys.

32. The combination with a set of type-operating numeral keys, a letter-feeding carriage controlled by said keys, two primary elements whereof one is connected to said carriage, one of said primary elements comprising a master-wheel and the other comprising a set of computing wheels, devices for enabling the keys on the down 50 strokes thereof to control the operation of said master-wheel, means for effecting disconnection between the keys and the master-wheel controlling devices at the down strokes of the keys, and means to cause the 55 master-wheel controlling devices to return to normal positions in advance of the keys.

33. The combination of a letter-feeding carriage having a toothed wheel, two primary elements comprising a master-wheel

and a set of computing wheels, one of said primary elements connected to said carriage, a spring to effect relative shifting of said primary elements to bring the master-wheel into engagement with the live computing wheel anticipatively of the feeding 70 movement of said carriage, and a pallet moved by said spring into the path of a tooth of said toothed wheel, to be driven by said tooth during the ensuing feeding motion of the carriage, and caused thereby 75 to maintain the engagement of said master-wheel with said live computing wheel during said carriage-feeding movement; said pallet constructed to escape from said toothed wheel at about the conclusion of 80 the letter-feeding movement of said carriage, to be caused by said spring to move into the path of the succeeding tooth coincidentally with the jumping of the shiftable primary element.

34. The combination with a computing mechanism, a source of power for driving the same, and a set of numeral keys, of means connected to said keys for causing the computing mechanism to be started into 90 action by the source of power, and means for automatically breaking the connection between said keys and said computing mechanism after such starting of the computing mechanism into action; said source 95 of power being constructed and connected to actively continue the operation of the computing mechanism regardless of such disconnection from the keys.

35. The combination with a computing 100 mechanism, a source of power for driving the same, and a set of numeral keys, of means connected to said keys for causing the computing mechanism to be started into action by the source of power, means for 105 automatically breaking the connection between said keys and said computing mechanism after such starting of the computing mechanism into action; said source of power being constructed and connected to actively 110 continue the operation of the computing mechanism regardless of such disconnection from the keys, and means for re-completing the connection after said computing mechanism has completed its action.

36. The combination with a computing mechanism, a source of power for driving the same, and a set of numeral keys controlling said computing mechanism through said source of power, of means for breaking 120 the connection between the keys and the computing mechanism during a key stroke, said source of power being constructed and connected to actively continue operation of the computing mechanism regardless of such 125 disconnection from the keys, means for starting the computing mechanism into action after the breaking of said connection,

means brought into action by any key for determining how much the computing mechanism shall move, and means for re-completing the connection after said computing mechanism has completed its action.

37. The combination with a computing mechanism, including a power-driven master wheel, of a set of numeral keys for starting the action of said computing mechanism, the latter including means controlled by the keys for limiting the rotation of the master wheel, and means for automatically effecting a disconnection between said computing mechanism and any key after the starting of said computing mechanism into action, to permit the rotation of the master wheel to be completed independently of the return of the operated key to normal position.

38. The combination with a computing mechanism, including a power-driven master wheel, of a set of numeral keys for starting the action of said computing mechanism, the latter including means controlled by the keys for limiting the rotation of the master wheel, and means for automatically effecting a disconnection between said computing mechanism and any key after the starting of said computing mechanism into action, to permit the rotation of the master wheel to be completed independently of the return of the operated key to normal position, means being provided for automatically re-connecting the computing mechanism to the key upon the return of the latter to normal position.

39. The combination with a computing mechanism, including a power-driven master wheel, of a set of numeral keys, means controllable by any of said keys for causing said master wheel to rotate, key-controlled means for variably limiting the extent of rotation, and means driven by the keys for disconnecting them from all of said key controlled means.

40. The combination with a set of numeral keys, of a master wheel controlled thereby, and automatic means for freeing the master wheel from the keys during the action thereof to enable the master wheel to complete its movement independently of the keys.

41. The combination with computing mechanism including a power-driven master wheel, a set of computing wheels operable successively thereby, and a set of numeral keys, of a member common to said keys for controlling the rotation of the master wheel, individual devices controllable by said keys for limiting the extent of rotation of the master wheel, and means to disconnect the keys from said common member and from said individual devices.

42. The combination with computing mechanism including a power-driven master

wheel, a set of computing wheels operable successively thereby, and a set of numeral keys, of a member common to said keys for controlling the rotation of the master wheel, and individual devices controllable by said keys for limiting the extent of rotation of the master wheel, each key having a single trip effective upon the down stroke of the key for disconnecting the latter from both its individual device and said common member.

43. The combination with computing mechanism including a power-driven master wheel, a set of computing wheels operable successively thereby, and a set of numeral keys, of a member common to said keys for controlling the rotation of the master wheel, individual devices controllable by said keys for limiting the extent of rotation of the master wheel, each key having a disconnecting means effective upon the down stroke of the key for disconnecting the latter from both its individual device and said common member, and means for enabling said keys on their up strokes to effect relative feeding movements between the master wheel and the computing wheels.

44. The combination with a power-driven master wheel, computing wheels operable successively thereby, and a set of numeral keys, of a member common to said keys for controlling the starting of the master wheel; means being provided for causing the rotation of the master wheel to be completed independently of said common member, and means controlled by the keys for determining the extent of rotation of the master wheel.

45. The combination with a computing mechanism, of a normally stationary power-driven master wheel, and computing wheels operable successively thereby, of means common to the keys for setting said master wheel in rotation, a disconnecting contrivance being provided between the keys and said means, so that the latter may complete its rotation independently of the operated key, and means individual to said keys for controlling the extent of rotation of the master wheel.

46. The combination with a normally stationary power-driven master wheel, computing wheels operable successively thereby, and a set of numeral keys, of a member common to said keys for controlling the start of the master wheel, and individual members operated by said keys for determining the extent of rotation of the master wheel, said common member and said individual members being controllable by the keys only upon the down stroke of the keys, and constructed and operated to permit the computations to be concluded independently and in advance of the return strokes of the keys.

47. The combination with a master wheel,

- 5 a motor to drive the same, computation wheels operable successively by the master wheel, and a set of numeral keys, of a member common to said keys for controlling the connection between the motor and the master wheel to cause the latter to be driven by the motor, means between the keys and said common member to enable the down-stroke of any key to cause the complete operation 5 of said common member, whereby the master wheel is rotated independently of the up-stroke of the key, and means individual to the keys and settable by the down-strokes thereof, for variably limiting the rotation 10 of the master wheel.
- 10 48. The combination with a master wheel, a motor to drive the same, computing wheels operable successively by said master wheel, and a set of numeral keys, of means for 20 enabling the keys to control the rotation of the master wheel by said motor and to determine the extent of rotation of the master wheel; means being provided to release said master wheel entirely from the control of said keys on the down-strokes of the latter, and for restoring the control of the keys 25 upon the return strokes thereof.
- 15 49. The combination with a master wheel, a motor to drive the same, computation wheels, a set of numeral keys, and a carriage 30 for effecting step-by-step movements between the master wheel and the set of numeral keys, of means brought into use by the keys on the down-strokes thereof for 35 causing the master wheel to be rotated by the motor and to be arrested, and means operable upon the up-strokes of the keys for causing the carriage to feed.
- 20 50. The combination with a master wheel, a motor to drive the same, computation 40 wheels, a set of numeral keys, and a carriage for effecting step-by-step movements between the master wheel and the set of numeral keys, of means brought into use by 45 the keys on the down strokes thereof for causing the master wheel to rotate and be arrested and also to become released from the control of the keys, and means operable upon the up-strokes of the keys for causing 50 the carriage to feed; means being provided for automatically reestablishing the control of the keys over the master wheel upon the return of the keys to normal positions.
- 25 51. The combination with a series of computing 55 wheels, a typewriter carriage and a master wheel, of means to enable the master wheel to turn the computing wheels, both when the carriage is stationary and when the carriage is moving.
- 30 52. The combination with computing 60 wheels, a typewriter carriage and a master wheel, of means for enabling the master wheel to jump to the live computing wheel in advance of the movement of the carriage.
- 35 53. The combination with a master wheel and computing wheels, of a carriage traveling to effect a relative movement of said master wheel and said computing wheels to bring said master wheel into successive register with each of said computing wheels, 70 and compensating means to enable the master wheel to turn the computing wheels both when the carriage is stationary and when the carriage is moving.
- 40 54. The combination with numeral keys, 75 computation wheels or members, a master wheel, an indexing device to control the rotation of said master wheel, and independent connections between said keys and said indexing device, of means for causing the 80 indexing device and master wheel to rotate independently of the keys.
- 45 55. The combination of numeral keys, a master wheel, computing wheels operable by the master wheel, indexing devices for 85 said master wheel and means controlled by any numeral key whereby said key may on its down stroke, control the extent of rotation of the indexing devices, cause said devices to rotate and disable itself from controlling said means.
- 50 56. The combination of numeral keys, a master wheel, computing wheels operable by the master wheel, an indexing device for 90 said master wheel, and means whereby any key during its down stroke may cause the indexing device to rotate, determine the extent of its rotation, and also disable itself from controlling said indexing device, means being provided for operatively re-connecting the key to the indexing device upon the return stroke of the key.
- 55 57. The combination with a computing mechanism, of a series of numeral keys, connections from said keys to control the action 95 of said computing mechanism, a traveling carriage, said keys and connections having an initial and a return stroke, said computing mechanism being started into operation 100 during the return stroke of said connections and said carriage being controlled by said keys during their return stroke, said keys and connections being releasable to enable said connections to begin their return and thereby start said computing mechanism 110 into operation during the initial stroke of said key and before any carriage movement.
- 60 58. The combination with a computing mechanism, of a series of numeral keys for 115 controlling said computing mechanism, and individual connections between said numeral keys and said computing mechanism, each of said connections camming itself free so as to break the control of an actuated numeral key over said computing mechanism 120 after a predetermined movement of the key.
- 65 59. The combination with a computing mechanism, of a series of numeral keys for 125 controlling the action of said computing mechanism, normally complete individual 130 .

connections between said numeral keys and said computing mechanism, and means acting at the depression of any key to interrupt the connection corresponding to that key, so as to free the computing mechanism from 5 subservience to such key after a predetermined movement thereof.

60. The combination with a computing mechanism, of a series of numeral keys for controlling the action of said computing mechanism, and individual connections from 10 said numeral keys to said computing mechanism, each connection acting by its continued movement after effecting the determination of extent of action of said computing mechanism to cause itself to disconnection.

61. The combination with a series of computing wheels, of a master wheel for 20 driving said computing wheels *seriatim*, a traveling carriage, and means controlled from said carriage for governing the relative step-by-step movement between said master wheel and said computing wheels, 25 acting to maintain said master wheel always in register with a computing wheel when in a computing zone while said carriage is moving.

62. The combination with a computing 30 mechanism, of a series of numeral keys of connections from said keys to control the action of said computing mechanism, said keys and connections having an initial and return stroke, said computing mechanism being started in operation during the return 35 stroke of said connections, said keys and connections being releasable on the initial stroke of said keys to enable said connections to begin their return and thereby start 40 said computing mechanism into operation during the initial stroke of said keys.

63. The combination with a computing mechanism, of a series of numeral keys for controlling the action of said computing 45 mechanism, mechanical connections between said numeral keys and said computing mechanism enabling said numeral keys to start said computing mechanism in action, and means for breaking the mechanical connection 50 between an actuated numeral key and said computing mechanism at a predetermined point in the movement of said key, enabling the completion of the computation by said computing mechanism independently of the further progress of the actuated numeral key.

64. The combination with a computing mechanism, of a series of numeral keys for controlling the action of said computing 60 mechanism, a series of linkages forming mechanical connections between said numeral keys and said computing mechanism, and automatically acting means for breaking the mechanical connection between the 65 actuated numeral key and the computing

mechanism so as to render the completion of the computing action of the computing mechanism started by the actuated numeral key independent of the further progress of the actuated numeral key.

65. The combination with a computing mechanism, of a series of numeral keys controlling the action of said computing mechanism, an individual linkage train connecting each numeral key with said computing mechanism, and automatically acting means for breaking the linkage train from an actuated numeral key to the computing mechanism after the linkage train has initiated a computing action of said computing mechanism, enabling the completion of the computing action initiated irrespective of a subsequent action of the actuated numeral key, said linkage train automatically completing itself on a subsequent return of the accord- 70 75 80 85 ant numeral key to its normal position.

66. The combination with a computing mechanism, of a series of numeral keys controlling the action of said computing mechanism, a series of mechanical connecting trains joining said numeral keys with said computing mechanism, and an obstruction lying in the path of movement of each of said trains, acting during an operation of the corresponding key to break the particu- 90 95 lar mechanical train in action.

67. The combination with a computing mechanism, of a series of numeral keys controlling the action of said computing mechanism, individual connections between said computing mechanism and each of said numeral keys, and means acting at the depression of a numeral key, to interrupt solely the individual connection joining that particular numeral key with said computing mechanism after such numeral key has started a computing action of said computing mechanism, so that said computing mechanism may complete the initiated action irrespective of the subsequent action of the actuated 100 105 110 numeral key previous to its return to its normal unactuated position.

68. The combination with a computing mechanism, including a gang of computing wheels and a master wheel for driving said 115 computing wheels *seriatim*, of an escapement mechanism for affording a relative movement between said gang of computing wheels and said master wheel, so as to bring about the successive register of said master wheel 120 with each of said computing wheels, a traveling carriage for controlling the relative movement between said computing wheels and said master wheel, an escapement mechanism for said carriage, a series of numeral 125 keys for controlling the action of said carriage escapement mechanism and also the action of said computing mechanism, and means for operating the escapement mechanism for said computing mechanism inter- 130

mediate the successive actuations of said escapement mechanism for said carriage.

69. The combination with a gang of computing wheels, of a master wheel for rotating said computing wheels, said master wheel having a jump movement to come into successive register with each of said computing wheels, a traveling carriage for enabling jump movements of said master wheel, numeral keys for controlling the travel of said carriage and the rotation of said master wheel, and automatic means for anticipating a jump movement of said master wheel to be effected by said carriage.
70. The combination with a gang of computing wheels, of a master wheel for rotating said computing wheels, said master wheel having a jump movement to come into successive register with each of said computing wheels, a traveling carriage for enabling the jump movements of said master wheel, numeral keys for controlling the travel of said carriage and the rotation of said master wheel, automatic means for anticipating a jump movement of said master wheel to be effected by said carriage, and including compensating means for allowing for the subsequent movement of said carriage while maintaining said master wheel in register with the computing wheel with which it has jumped in its anticipating movement.
71. The combination with a gang of computing wheels, of a master wheel for driving said computing wheels *seriatim*, said computing wheels and said master wheel having a relative traveling movement to bring said master wheel *seriatim* into register with each of said computing wheels, a carriage for controlling the relative movement between said master wheel and said computing wheels, and automatic means for anticipating said relative movement to bring about the registration of each computing wheel with said master wheel.
72. The combination with a gang of computing wheels, of a master wheel for driving said computing wheels *seriatim*, said computing wheels and said master wheel having a relative traveling movement to bring said master wheel *seriatim* into register with each of said computing wheels, a carriage for controlling the relative movement between said master wheel and said computing wheels, automatic means for anticipating said relative movement to bring about the registration of each computing wheel with said master wheel, and including compensating means for allowing said carriage to catch up with the anticipated relative travel between said computing wheels and said master wheel while maintaining the master wheel in register with the computing wheel with which it has engaged by said anticipating relative movement.
73. The combination with two primary
- elements, to wit, a series of computing wheels and a master wheel for driving said computing wheels *seriatim*, of a carriage connected to control a relative movement between said computing wheels and said master wheel so as to enable successive registering of said master wheel with each of said computing wheels, and compensating means enabling the drive of said computing wheels by said master wheel both while said carriage is stationary and while said carriage is traveling.
74. The combination with a series of computing wheels, of a master wheel for driving said computing wheels *seriatim*, and a traveling carriage connected to control a relative movement between said computing wheels and said master wheel so that said master wheel may register successively with each of said computing wheels, the relative movements of said master wheel and said computing wheels taking place intermediate the movements of said carriage.
75. The combination with two primary elements including a gang of computing wheels and a master wheel for driving said computing wheels, said primary elements having a relative travel to bring said master wheel into successive register with each of said computing wheels, of a series of numeral keys for controlling both the extent of rotation of said master wheel and the relative travel between said primary elements, and compensating means for lengthening the period of engagement of the master wheel with the live computing wheel, including means for anticipating the relative movement between said primary elements.
76. The combination with a computing mechanism, of a series of numeral keys for controlling the action of said computing mechanism, connections between said numeral keys and said computing mechanism enabling the control of said computing mechanism by said numeral keys, and means for completing a computing action by said computing mechanism, brought into play by the breaking of an actuated connection at the stroke of a numeral key, whereby computation can be effected solely when the control by the actuated numeral key of the computing mechanism is interrupted.
77. The combination with a computing mechanism, of a series of numeral keys connected to control the action of said computing mechanism, and means brought into action by the interruption of the control by any numeral key of said computing mechanism, to start said computing mechanism into action to compute a number corresponding to the numeral key having its control so interrupted.
78. The combination with a computing mechanism including two primary elements, to wit, a gang of computing wheels and a master wheel for driving said computing

- wheels *seriatim*, said primary elements having a relative traveling movement to bring said master wheel into successive register with each of said computing wheels, of a traveling carriage connected to enable said relative movement between said primary elements, a series of numeral keys connected to control the traveling movements of said carriage at a definite point in the stroke of each 5 numeral key, said numeral keys being also connected to control the action of said computing mechanism, including the instant and extent of rotation of said master wheel at a definite point in the movement of a numeral 10 key, and compensating means for synchronizing the period of rotation of said master wheel with the period of registry of the master wheel with the computing wheel to be rotated.
- 15 79. The combination with a computing mechanism, including two primary elements, to wit, a gang of computing wheels and a master wheel for driving said computing wheels *seriatim*, said primary elements having a relative traveling movement to bring said master wheel into successive register with each of said computing wheels, of a traveling carriage connected to enable said relative movement between said primary elements, a series of numeral keys connected to control the traveling movements of said carriage at a definite point in the stroke of each 20 numeral key, said numeral keys being also connected to control the action of said computing mechanism including the instant and extent of rotation of said master wheel at a definite point in the movement of a numeral key, and timing means for asynchronizing the periods of rest of said carriage and said 25 primary elements.
- 30 80. The combination with a computing mechanism, including two primary elements, to wit, a gang of computing wheels and a master wheel for driving said computing wheels *seriatim*, said primary elements having a relative traveling movement to bring said master wheel into successive register with each of said computing wheels, of a traveling carriage connected to enable relative movement between said primary elements, a series of numeral keys connected to control the traveling movements of said carriage and the action of said computing mechanism, and timing means for effecting at 35 widely different portions of the numeral-key stroke the initial actuation of the computing mechanism and the initial traveling movement of the carriage.
- 40 81. The combination with a computing mechanism, including two primary elements, to wit, a gang of computing wheels and a master wheel for driving said computing wheels *seriatim*, said primary elements having a relative traveling movement to bring

said master wheel into successive register 45 with each of said computing wheels, of a traveling carriage connected to enable said relative movement between said primary elements, a series of numeral keys connected to control the traveling movements of said carriage at a definite point in the stroke of each 50 numeral key, said numeral keys being also connected to control the action of said computing mechanism, including the instant and extent of rotation of said master wheel at a definite point in the stroke of a numeral key, and means for advancing the period of 55 computing action as related to the key stroke, to effect at widely different portions of the numeral-key stroke the initial actuation of the computing mechanism and the initial traveling movement of the carriage.

82. The combination with a computing mechanism, of a series of numeral keys connected to control the action of said computing mechanism, and means for enabling the action of said computing mechanism to be started on the down stroke of and to continue during a period overlapping a considerable portion of the up stroke of the 90 actuated numeral key.

83. The combination with a computing mechanism including a series of computing wheels and a master actuator movable relatively to each other, a series of numeral keys 95 to control the operation of said master actuator, a traveling carriage controlled in its movement by said numeral keys and controlling the relative movement of the computing wheels and actuator, a computing drive of 100 a computing wheel by the master actuator depending upon the period of registry of the master actuator with that computing wheel; of means for increasing the possible period of each operation of said actuator 105 comprising devices permitting the computing action to overlap the period of movement of the operated numeral key, and to enable a movement of the carriage, while no relative movement between the computing 110 mechanism and actuator takes place.

84. The combination with a computing mechanism including a series of computing wheels and a master actuator movable relatively to each other, a series of numeral keys 115 to control the operation of said master actuator, a traveling carriage controlled in its movement by said numeral keys and controlling the relative movement of the computing wheels and actuator, a computing drive of a computing wheel by the master actuator depending upon the period of registry of the master actuator with that computing wheel; of means for increasing the possible period of each operation of said actuator 120 comprising devices permitting the computing action to overlap the period of movement of the operated numeral key, and 125

to enable a movement of the carriage, while no relative movement between the computing mechanism and actuator takes place, said last-named means including means for

5 interrupting the connection between said numeral keys and said computing mechanism after a predetermined movement of a numeral key.

85. The combination with a computing mechanism including two primary elements, 10 to wit, a series of computing wheels and a master actuator movable relatively to each other; a series of numeral keys to control the operation of said master actuator, a traveling carriage controlled in its movement by 15 said numeral keys and controlling the relative movement of the computing wheels and actuator, a computing drive of a computing wheel by the master actuator depending upon the period of registry of the master actuator with that computing wheel; of 20 means for increasing the possible period of each operation of said actuator comprising devices permitting the computing action to 25 overlap the period of movement of the operated numeral key, and to enable a movement of the carriage, while no relative movement between the computing mechanism and actuator takes place, said last-named means including 30 a break-and-make connection between said numeral keys and said computing mechanism, and a flexible connection between said carriage and said primary elements, whereby the instant of relative movement 35 between said primary elements will be offset with respect to the instant of movement of said carriage.

86. The combination with a computing mechanism including two primary elements, 40 to wit, a series of computing wheels and a master actuator movable relatively to each other; a series of numeral keys to control the operation of said master actuator, a traveling carriage controlled in its movement by 45 said numeral keys and controlling the relative movement of the computing wheels and actuator, a computing drive of a computing wheel by the master actuator depending upon the period of registry of the master actuator with that computing wheel; of 50 means for increasing the possible period of each operation of said actuator comprising devices permitting the computing action to overlap the period of movement of the operated numeral key, and to enable a 55 movement of the carriage, while no relative movement between the computing mechanism and actuator takes place, said last-named means including automatically breaking 60 connections between the numeral keys and the computing mechanism for interrupting the control of the computing mechanism by the actuated numeral key after a predetermined movement of the latter, and

connections between one of the primary elements and said carriage for enabling said primary element to remain stationary while said carriage is moving.

87. The combination with a computing mechanism including two primary elements, 70 to wit, a gang of computing wheels and a master wheel for driving said computing wheels individually, of a traveling carriage, said primary elements having a relative movement to bring said master wheel into 75 successive register with each of said computing wheels, and compensating connections between said carriage and said primary elements to enable a movement of the carriage, while no relative movement between 80 said primary elements takes place.

88. The combination with a computing mechanism including two primary elements, 85 to wit, a gang of computing wheels, and a master wheel for driving said computing wheels individually, of a traveling carriage, said primary elements having a relative movement to bring said master wheel into successive register with each of said computing wheels, and compensating connections 90 between said carriage and said primary elements to enable a movement of the carriage, while no relative movement between said primary elements takes place, said compensating connections including a lever capable of rocking about two different points as fulcrums.

89. The combination with a computing mechanism including a gang of computing wheels and a master wheel for driving said 100 computing wheels individually, of a traveling carriage, said primary elements having a relative movement to move said master wheel into successive register with each of said computing wheels, and compensating 105 connections between said carriage and said primary elements to enable a movement of the carriage, while no relative movement between said primary elements takes place, said compensating connections including a 110 lever having a floating pivot point which sometimes acts as a pivot and sometimes moves to accommodate a passive swing of the lever.

90. The combination with a computing 115 mechanism including two primary elements, to wit, a gang of computing wheels and a master wheel for driving said computing wheels individually, of a traveling carriage, said primary elements having a relative 120 movement to bring said master wheel into successive register with each of said computing wheels, and compensating connections between said carriage and said primary elements to enable a movement of the 125 carriage, while no relative movement between said primary elements takes place, said compensating connections including a

hook connectible to said carriage, a rocking lever connected to said hook and a carriage having a pivotal point of connection to said lever, said last-mentioned carriage being connected to traverse one of said primary elements, and said lever being floatingly mounted so that said pivotal point of connection sometimes acts as a stationary point while said lever swings and sometimes acts as a moving point while said lever swings.

91. The combination with a computing mechanism including two primary elements, to wit, a gang of computing wheels and a master wheel for driving said computing wheels individually, of a traveling carriage, said primary elements having a relative movement to bring said master wheel into successive register with each of said computing wheels, and compensating connections between said carriage and said primary elements to enable a movement of the carriage, while no relative movement between said primary elements takes place, said compensating means including a train of linkages between said carriage and one of said primary elements, enabling the traversing of said primary elements by said carriage, means for intermittently joining said train of linkages with said carriage to be operated by said carriage, and means for modifying the action of said train of linkages, so that at times it operates as a positive driving means and at other times moves passively without disturbing the primary element with which it maintains its connection.

92. The combination with a computing mechanism including two primary elements, to wit, a gang of computing wheels and a master wheel, said primary elements having a relative traveling movement to enable said master wheel to register successively with each of said computing wheels, of a traveling carriage, an escapement for controlling the traveling movements of said carriage, a train of connections between said carriage and said primary elements for causing the relative movement between said primary elements, and means operated by said escapement for modifying the action of said train of connections to enable a movement of the carriage, while no relative movement between said primary elements takes place.

93. The combination with a computing mechanism including two primary elements, to wit, a gang of computing wheels and a master wheel for driving said computing wheels individually, said primary elements having a relative movement to enable the *seriatim* register of said master wheel with each of said computing wheels, of a traveling carriage, a train of connections enabling said carriage to cause a relative step-by-step movement between said primary elements for a number of computing zones or col-

umns, means for operating said train of connections in the opposite direction to bring about an initial relative positioning between said primary elements, and means for modifying the action of said train of connections so that the relative movements between said primary elements will be out of step with the corresponding movements of said carriage.

94. The combination with a computing mechanism including two primary elements, one being a master wheel and the other a set of computing wheels individually rotatable by said master wheel, of a traveling carriage, a train of connections between said traveling carriage and one of said primary elements to cause the latter to travel under control of movements of said carriage, compensating means in said connections including a lever, a support for said lever about which said lever is adapted to rock, and automatic means for shifting said support to anticipate a movement of said traveling element as determined by a movement of said carriage.

95. The combination with an indexing device for determining the extent of a computation, of a series of numeral keys connected to set said indexing device for a computation corresponding to the key actuated, a universal member common to all of said numeral keys, so as to be actuated at the depression of any of said numeral keys, said universal member being connected to initiate a computing action of said indexing device on the return movement of said universal member, and means for interrupting the connection between an actuated numeral key and said universal member prior to the return of the actuated numeral key, so that said universal member may return and initiate a computing action of said indexing device prior to the return of the actuated numeral key.

96. The combination with an indexing device settable to determine the extent of a computation, of a series of numeral keys for setting said indexing device for a computing action corresponding to the numeral key actuated, a motor for driving said indexing device an amount corresponding to the computation set up therein, a universal member common to all of said numeral keys so as to be actuated on the depression of any of said numeral keys, acting on its return movement to control the drive of said indexing device by said motor, and disconnecting means for interrupting the control by the depressed numeral key of said universal member prior to the return of said depressed numeral key, so that said universal member may return and initiate a drive of said indexing device by said motor prior to the return of the actuated numeral key.

97. The combination with a computing

- mechanism, of a series of numeral keys for controlling said computing mechanism, setting means actuated by said numeral keys to set up a computation in said computing mechanism, driving means for actuating said computing mechanism dependent for its action on the return of said setting means after having been actuated, and interrupting means for breaking the control by the actuated numeral key of said setting means after the function of the latter has been accomplished, so that said computing mechanism may be driven by said driving means independently of the subsequent action of the operated numeral key.
98. The combination with a computing mechanism, of a series of numeral keys for controlling the action of said computing mechanism, individual trains of connection between said numeral keys and said computing mechanism, said computing mechanism remaining passive until after the control from a numeral key actuated has been silenced, and means for effecting the silencing of the control between said computing mechanism and an actuated numeral key by breaking the train of connection between said numeral key and said computing mechanism during the stroke of said numeral key, so that said computing mechanism may start into action irrespective of the subsequent movement of such actuated numeral key.
99. The combination with numeral keys, computing wheels or members, a master wheel or member, an indexing device to drive said master wheel, and connections between said keys and said indexing device, of means operatively connected with said keys for causing the indexing device and master wheel to rotate during the down stroke of any key, and means for effecting operative disconnection between the key and indexing device during the down stroke of the key.
100. The combination with a master wheel, a motor to drive the same, computation wheels operable successively by the master wheel, and a set of numeral keys, of a member common to said keys for controlling the connection between the motor and the master wheel, to cause the latter to be driven by the motor, means operable by the down-strokes of any of the keys to first actuate and then release or disconnect the key from said common member, means to reconnect the keys to the common member at the up-strokes of the keys, and means individual to the keys and settable by the down-strokes thereof, for variably limiting the rotation of the master wheel.
101. A combined typewriting and computing machine having computing members, a master member for driving said computing members *seriatim*, and a typewriter carriage having a step-by-step movement for controlling the engagement *seriatim* of said master member and computing members; and comprising in combination therewith means enabling the simultaneous drive of a computing member and stepping movement of said carriage.
